US0D1085077S

(12) **United States Design Patent** (10) **Patent No.:** **US D1,085,077 S**
(45) **Date of Patent:** **** Jul. 22, 2025**

(54) **NOTEBOOK COMPUTER**

(71) Applicant: **Acer Incorporated**, New Taipei (TW)

(72) Inventors: **Wei-Chang Chen**, New Taipei (TW);
Jung-Wei Tsao, New Taipei (TW);
Ker-Wei Lin, New Taipei (TW)

(73) Assignee: **Acer Incorporated**, New Taipei (TW)

(**) Term: **15 Years**

(21) Appl. No.: **29/891,519**

(22) Filed: **May 7, 2023**

(30) **Foreign Application Priority Data**

Feb. 3, 2023 (TW) 112300431

(51) **LOC (15) Cl.** **14-02**

(52) **U.S. Cl.**

USPC **D14/315**; D14/440

(58) **Field of Classification Search**

USPC D14/315-328, 345, 440-441, 444-446;
D3/288, 321, 900, 902

CPC G06F 2200/1633; G06F 2200/1634; G06F
1/1656

See application file for complete search history.

(57) **CLAIM**

The ornamental design for a notebook computer as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The even-dashed broken lines shown in the drawings illustrate portions of the notebook computer that form no part of the claimed design.

1 Claim, 8 Drawing Sheets
